UNITED STATES PATENT OFFICE.

THOMAS M. McKELVY, OF FRESNO, CALIFORNIA.

OIL-VAPOR BAFFLE BOX

Application filed April 10, 1922. Serial No. 551,430.

To all whom it may concern.

Be it known that I, THOMAS M. Mc-
KELVY, a citizen of the United States, re-
siding at Fresno, in the county of Fresno
5 and State of California, have invented cer-
tain new and useful Improvements in Oil-
Vapor Baffle Boxes; and I do hereby de-
clare the following to be a full, clear, and
exact description of the invention, such as
10 will enable others skilled in the art to which
it appertains to make and use the same.

This invention relates to new and useful
improvements in oil vapor boxes for in-
ternal combustion engines and has for its
15 primary object the provision of a device
of the above stated character whereby gases
may be conveyed from the crank case of
an engine to the carburetor without oil va-
por for the purpose of mixing with the fuel
20 and to enter the explosive chambers to be
compressed and ignited and thereby render
a saving in fuel and providing a scaveng-
ing medium to the crank case.

Another object of this invention is the
25 provision of an oil vapor baffle box of the
above stated character which will be sim-
ple, durable and efficient, and which may
be manufactured and sold at a comparative-
ly low cost.

30 With these and other objects in view,
as will become more apparent as the de-
scription proceeds, the invention consists
in certain novel features of construction,
combination and arrangement of parts as
35 will be hereinafter more fully described
and claimed.

For a complete understanding of my in-
vention, reference is to be had to the fol-
40 lowing description and accompanying draw-
ings, in which:

Figure 1 is a side elevation, illustrating
an engine with my invention applied
thereto,

Figure 2 is a front elevation, illustrat-
45 ing the box located in the priming gear
chamber of an engine,

Figure 3 is a sectional view, illustrat-
ing the box,

Figure 4 is a sectional view, taken on
50 the line 4-4 of Figure 2.

Referring in detail to the drawings, the
numeral 1 indicates an internal combus-
tion engine equipped with an intake mani-
fold 2 having a carburetor 3. The engine
55 1 is provided with the usual crank case
4 and timing gear chamber 5 in commun-
ication with the crank case 4 and closed
by a removable wall 6. The foregoing de-
scription relates to a well known construc-
tion of engine to which my invention is
60 applied and the rear wall 7 of the cham-
ber 5 has formed therein a conduit or pas-
sage 8, one end of which opens outwardly
through one side of the cylinder block of
the engine 1 and has connected thereto
65 a pipe 9 which is in turn connected to the
air intake of the carburetor 3, while the
other end of said conduit or passage 8 opens
outwardly through the wall 7 into the
chamber 5. Between the last named end
70 of the conduit 8 and the crank case 4 of
the engine is an oil deflector 10 comprising
a curved plate 11 which has its up-
per edge detachably secured to the wall 7
above the conduit 8 by a bolt 12, while
75 the lower portion of said plate extends
in parallelism with the cover 6 and in close
proximity thereto. Bolts 13 also secure the
plate 11 to the wall 7 below the conduit 8
and supports a screen 14 through which
80 the gases leaving the crank case and enter-
ing the carburetor must pass and as the
gases leave the crank case they contain a
certain amount of oil vapor which is re-
moved from the gases when the latter pass
85 through the screen and the oil vapor ac-
cumulates on the screen and falls by grav-
ity back into the crank case, thus retain-
ing the lubricant within the crank case and
obviating the passage of the same into the
90 carburetor. The screen 14 comprises a
skeleton frame 15 of triangular shape in
cross section which has its apex disposed
lowermost with its side portions mounted
on the bolts 13. The sides and ends of the
95 frame are covered with foraminous ma-
terial 16 for the purpose of forming a
screen. The gases, after passing through
the screen, are directed into the conduit 8
by the curved portion of the plate 11 and
100 prevented from passing into the upper end
of the chamber 5.

From the foregoing description taken in
connection with the accompanying draw-
ings, it should be apparent that a device is
provided which can be easily and conven-
iently installed on an internal combustion
engine so that the gases accumulating with-
in the crank case of the engine may be con-
veyed to the carburetor for mixing with
110 the fresh fuel without any liability of oil
vapor passing into the carburetor to inter-

fer with the proper fuel entering the engine or explosive chambers thereof and also prevent a waste of the lubricant as would be the case if the oil vapor were permitted 5 to escape from the crank case, and further the device provides a very effective scavenging medium to the crank case whereby the gases escaping by the piston of the engine into the crank case may be again utilized 10 for fuel by entering the carburetor and becoming mixed with fresh fuel, consequently providing a saving of fuel in the operation of the engine.

While I have shown and described the 15 preferred embodiment of my invention, it will be understood that minor changes in construction, combination and arrangement of parts may be made without departing from the spirit and scope of the invention 20 as claimed.

Having thus described my invention what I claim is:

1. In combination with a chamber having a passageway in communication with the 25 fuel line of an internal combustion engine and open at one side thereof, an oil trap means consisting of a screen disposed in the path of travel of oil vapor to said passageway, a deflector plate extending upwardly 30 from the screen adjacent one side thereof and over the screen and terminating adjacent the plane of the other side of and above the screen to deflect material to said passageway.

2. In combination with a chamber having 35 a passageway in communication with the fuel line of an internal combustion engine and open at one side thereof, an oil trap means consisting of a screen disposed in the path of travel of oil vapor to said passageway, a deflector plate extending upwardly from the screen adjacent one side thereof and over the screen and terminating adjacent the plane of the other side of and above the screen to deflect material to said 40 passageway, and fastening means extending through the deflector and screen into the chamber and adjacent the base of said passageway.

3. An oil trap means consisting of a 50 screen disposable in the path of travel of oil vapor and being substantially V-shape in cross section and with its apex lowermost, a deflector plate extending upwardly over one side of the screen 55 and then above and over the top of said screen, the upper edge of the plate terminating above and in spaced relation to the screen and constituting a fastening flange, and a fastening bolt passing through the 60 deflector plate and screen to secure them together and to a support.

In testimony whereof I affix my signature in presence to two witnesses.

THOMAS M. MCKELVY.

Witnesses:
